UNITED STATES PATENT OFFICE

145,572

DESIGN FOR A FINGER RING

Barnett Esh, New York, N. Y., assignor to Weisfield & Goldberg, Inc., Seattle, Wash., a corporation of Delaware

Application April 17, 1945, Serial No. 119,068

Term of patent 14 years

(Cl. D45—10)

To all whom it may concern:

Be it known that I, Barnett Esh, a citizen of the United States, residing at New York, in the county of New York and State of New York, have invented a new, original, and ornamental Design for a Finger Ring, of which the following is a specification, reference being had to the accompanying drawing, forming part thereof.

Figure 1 is a side elevational view of a finger ring, showing my new design,
Figure 2 is a top plan view, and
Figure 3 is an end elevational view thereof.
I claim:

The ornamental design for a finger ring, as shown.

BARNETT ESH.
